UNITED STATES PATENT OFFICE.

ARTHUR MONTGOMERIE CALLOW, OF LONDON, ENGLAND.

GRAB.

Application filed May 12, 1923. Serial No. 638,495.

To all whom it may concern:

Be it known that I, ARTHUR MONTGOMERIE CALLOW, a subject of the King of Great Britain, residing at 56 Cowcross Street, 5 London, E. C. 1, England, have invented a new and useful Improvement in Grabs, of which the following is a specification.

This invention relates to single chain grabs and has for its object to provide a 10 grab which shall be certain in operation and shall require the minimum of head room.

My invention will be readily understood by reference to the accompanying drawings and to the claiming clauses.

15 In the drawings Figure 1 is a vertical elevation showing the parts in the position they occupy when the bucket is resting open on the ground or on the material to be grabbed, one half of the bucket being removed; Figure 2 is a similar view showing the bucket closed with its weight carried by the rope; Figure 3 is a view at right angles to Figure 2 with the parts in the same position; Figure 4 is a view showing 20 the head looking in the same direction as in Figure 2, the hook having caught in a suspender ring. Figures 5 and 6 are views looking from the same direction as Figures 2 and 3 respectively but showing the bucket 25 open and suspended by the rope. Figure 30 7 is a section on the line *a—a* of Figure 1, and Figure 8 is a plan of the body. Figure 9 is a view illustrating how three suspender 35 rings can be employed to enable the bucket to be opened at three different levels.

A is the head from which the two halves B, B, of the bucket are suspended by side rods each of which is formed of two parts C, C¹, connected together by a hinge *c*. The 40 parts C are hinged to the head at *a*, *a*, and the parts C¹ are connected to the corners of the bucket at *b*, *b*. Links D, D, connect the hinges *c* to the main hinge pins E, E. The parts are so arranged that when the 45 bucket is closed as seen most clearly in Figure 3 the parts C and C¹ of each side rod are nearly in line with one another, but when the bucket is open as seen most clearly in Figure 6 the two parts C, C¹, are at a 50 considerable angle to one another, with the result that there is very little difference between the vertical over-all dimensions of the grab when open and closed. The head is formed of two side plates A, A, and two end plates F, F¹. Near to the plate F and supported by the side plates A, A, is a pin

5 on which is pivoted a frame consisting of two bars G, G, from the middle of each of which rises an arm G¹ of which the upper end is formed as a hook *g*, the two hooks 60 having between them a distance piece *g*¹ which acts as a guide roller for the operating rope H. To the two side plates A, A, are pivoted two downwardly extending links J, J, the lower ends of which are connected by rule joints *j* to two other double links K, K, pivoted to the body at *k*, *k*; one side of each link K, K, is prolonged below its pivot as seen clearly in the drawings. Pivoted to the body *l* is a rocking frame 70 L carrying a sheave M. The frame L is adapted to engage the bottom ends of the links K. The upper ends of the links J are formed as bell cranks, that is, they have forwardly extending arms J¹ which are linked 75 by links J² to the forward ends of the bars G. On a cross pin N which forms the pivot of the tops of the links J is mounted a guide roller *n* for the rope H. From the bars G is slung by links O the top sheave *o*. 80 On a cross pivot P carried in the head is mounted a bent arm Q to the bottom of which the rope is anchored. On the pivot P is mounted a guide roller *p*. The arm Q is prolonged above the pivot P and carries 85 a stud *q*. Hinged on a pin *r* in the head are two side plates R, R¹, forming a shroud; one R of these plates is prolonged downwards beyond its hinge and embraces the 90 stud *q*. In the upper parts of the two plates R, R¹, are slots S in which can move studs 95 *s*, *s*, carried by the hooks *g*, *g*. T is a sheave carried on a fixed pivot in the body. The rope passes down from the jib head between the hook arms G¹, G¹, between the guide 100 rollers *n* *p*, round the sheave M, up to and round the sheave *o*, down to and round the sheave T and so up to the arm Q.

The operation is as follows:—

Assuming the bucket to be resting upon 100 the ground or on the material to be grabbed, as shown in Figure 1, the rocking frame L will be in its lowest position, the knees of the toggle links J, K, will be just broken owing to the weight of the hooks *g*, *g*, 105 and the parts depending from them acting upon the bell crank arms J¹, J¹. On hauling in the rope H the bucket will close and the knees of the toggle links will collapse as shown in Figure 2, the bell crank 110 arms J¹ will turn the hooks *g*, *g*, into the position shown in Figure 2, while the

shroud R, R¹, will remain in its position owing to the pull of the rope on the arm Q. Therefore when the grab has been raised to such a height that the hooks and shroud 5 pass up through the suspension ring U the shroud will push the latter slightly to the right as seen in Figure 2. When the rope is slightly paid out the hooks will catch on the top of the ring as shown in Figure 10 4 and the grab will be suspended from the ring. On further paying out the rope the grab will open and discharge and when it is completely open the toggle links J, K, will straighten owing to the weight of the 15 bucket. On the rope being hauled in the rocking frame L, which had dropped when the tension was off the rope, will rise and engage the lower ends of the links K as shown in Figure 5, so that the toggle links 20 will be converted into rigid struts. Therefore as the rope is further hauled in the grab will be lifted in its open position and the hooks g, g, will rise above the ring U. The shroud R, R¹, is then in the position 25 in which it is shown in Figure 5, in which position the hooks will be shrouded so that they cannot again engage the ring, whereupon the open grab may be lowered on to the material. So soon as the load is taken 30 off the chain or rope the sheave M and its rocking frame L will drop out of engagement with the links K, K, and the toggle links J, K, will be free to break, and will at once be broken by the weight of the bars 35 G, G, and the parts depending therefrom acting upon them.

Should it be desired to discharge the grab at different levels two or three suspension rings may be provided as shown in 40 Figure 9. The top ring U is carried by chains u and additional rings V, V¹, are suspended from the ring U by chains v and by links W each formed in two parts connected by a rule joint w. The normal 45 position of the three rings is shown in Figure 9. Should it be desired to discharge from the top ring the head of the grab as it rises will raise the ring V¹ up to the ring V and then the two rings together 50 up to the ring U.

What I claim is:—

1. In a grab operated by a single chain, the combination of a head, a hook mounted 55 therein and adapted to engage a suspender ring, a body, a bucket consisting of two halves hinged to the body, side rods connecting the bucket halves to the head, a frame capable of turning about a horizontal axis in the body, a sheave journalled in this frame and toggle links pivoted to the head and to the body and adapted to be engaged by the said frame.

2. In a grab operated by a single chain, the combination of a head, a hook mounted 60 therein and adapted to engage a suspender

ring, a body, a bucket consisting of two halves pivoted to the body, two part side rods connecting the bucket halves to the head, a link connecting the two parts of each side rod to the body, a frame capable of turning about a horizontal axis in the body, a sheave journalled in said frame, and toggle links pivoted to the head and to the body and adapted to be engaged by the said frame. 75

3. In a grab operated by a single chain, the combination of a head, a frame pivoted on a horizontal axis in the head, a hook carried by the frame and adapted to engage a suspender ring, a top sheave carried by the frame, a body, a bucket consisting of two halves pivoted to the body, side rods connecting the bucket halves to the head, a sheave frame journalled in the body, a sheave thereon, and a suspension rope passing around the two sheaves. 85

4. In a grab operated by a single chain, the combination of a head, a frame pivoted on a horizontal axis in the head, a hook carried by the frame and adapted to engage a suspender ring, a top sheave also carried by the frame, a shroud pivoted to the head and adapted to shroud the hook so that it cannot engage the suspender ring, a body, a bucket consisting of two halves pivoted to the body, side rods connecting the bucket halves to the head, a sheave frame mounted on a horizontal axis in the body, a sheave mounted in the sheave frame, a third sheave pivoted to the body, a chain anchor pivoted to the head and engaging the shroud and a suspension rope passing down around the second sheave, around the top sheave, around the third sheave and connected to the anchor. 95 100 105

5. In a grab operated by a single chain, the combination of a head, a frame pivoted on a horizontal axis in the head, a hook carried by the frame and adapted to engage a suspender ring, a top sheave carried by the frame, a body, a bucket consisting of two halves pivoted to the body, side rods connecting the bucket halves to the head and each consisting of a part hinged to the head and a part hinged to the bucket, these two parts being hinged together, a link connecting the two parts of each side rod to the body, a sheave frame mounted in the body, a sheave thereon and a suspension rope passing around the two sheaves. 110 115 120

6. In a grab operated by a single chain, the combination of a head, a frame pivoted on a horizontal axis in the head, a hook carried by the frame and adapted to engage a suspender ring, a top sheave also carried by the frame, a shroud pivoted to the head and adapted to shroud the hook so that it cannot engage the suspender ring, a body, a bucket consisting of two halves pivoted to the body, side rods connecting the bucket 125 130

halves to the head and each consisting of a part hinged to the head and a part hinged to the bucket, these two parts being hinged together, a link connecting the two parts of each side rod to the body, a sheave frame mounted on a horizontal axis in the body, a sheave mounted in the sheave frame, a third sheave pivoted to the body, a chain anchor pivoted to the head and engaging the shroud

and a suspension rope passing down around the second sheave, around the top sheave, around the third sheave and connected to the anchor.

In testimony that I claim the foregoing as my invention I have signed my name this 15 third day of May, 1923.

ARTHUR MONTGOMERIE CALLOW.
